UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 35,799, dated March 11, 1902.

Application filed February 7, 1902. Serial No. 93,089. Term of patent 7 years.

To all whom it may concern:

Be it known that I, CHARLES J. AHRENFELDT, a citizen of the United States, residing at the city of New York, county of New York, and State of New York, have invented and produced a new and original Design for a Plate or Similar Article, of which the following is a specification, reference being had to the accompanying drawings, forming a part thereof.

In the said drawings, Figure 1 is a plan view of a plate with my design thereon. Fig. 2 is a vertical cross-section of the same.

The panel *a* consists of two interlocked shields having a scroll *a'* between their interlocking parts. From either side of this panel proceed triple-leafed ornaments *b*, and from the inner end of the same a similar ornament *b'*, supplemented by the group of stems bearing bud-like ornaments *c'*. The leafed ornaments at the sides and end of the panel are connected by smaller clusters of stems and buds *c*. On

either side of the centerpiece thus formed are scrolls *e* and *f*, and their ornaments *d*, similar to *c*. This ornamentation is repeated 25 a number of times, the different ornaments being connected by scrolls *i*, having leafed ornaments *g* projecting therefrom and bud-bearing stems *h*, similar to *b'* and *c'*, respectively, the whole forming a continuous border. The centerpiece consists of a panel *m*, having on its four sides ornaments *j* *k*, which are a repetition of *b'* *c'*, connected by budded stems *l*, similar to *c*.

What I claim is—

The design for a plate or similar article substantially as herein shown and described.

Signed at the city of New York, in the county of New York, this 29th day of January, 1902.

CHARLES J. AHRENFELDT.

Witnesses:
